ROTARY PUMP APPARATUS

Frank Christian Fulcher, Kentsbank, Grange-over-Sands, England

Application May 9, 1941, Serial No. 392,699
In Great Britain May 20, 1940

13 Claims. (Cl. 230—157)

The present invention relates to rotary vane pumps of the kind in which the vanes are mounted to rotate within a working chamber and pass through slots in the wall of a barrel-like rotor so as to project inside and outside the barrel which also rotates within the chamber about an axis eccentric to that about which the vanes rotate, so that a relative sliding movement between the vanes and the rotor is produced when the rotor and vanes turn and the ends of the vanes are carried round the peripheral wall of the working chamber. The invention is particularly but not exclusively applicable to high speed vacuum pumps for the operation of suction-driven instruments and gauges on aircraft or to pressure pumps for use as superchargers or blowers on aircraft for charging the cabin or other occupied interior of the aircraft with air at a greater pressure than that of the surrounding atmosphere as for example is necessary at high altitudes, or for use in the operation of deicing equipment. In some cases the pump serves the double duty of vacuum pump for operating instruments and as pressure pump for operating the de-icing apparatus. Vacuum pumps for the aforesaid purpose may run at speeds varying from 800 to 4,500 R. P. M., with a normal or cruising speed of the order of about 2,000 R. P. M., if the pump is driven direct from the engine. There are various classes of pump of the foregoing type to which the present invention can be applied. In some forms the vanes pass from one side of the working chamber to the other intersecting within the barrel. In other forms the inner ends of the vanes slide around a tube or cylinder arranged centrally of the working chamber or approximately so whilst the outer ends centrifuge against the inner wall of the working chamber. In some cases the vanes are constrained against centrifuging but do not pass completely through the barrel, e. g., the inner ends of the vanes may be provided with spaced intercalating eyes mounted upon a spindle centrally of the working chamber. In this latter class, in some cases, only the space in the working chamber around the barrel is utilized but I prefer to utilize not only that space but the space within the barrel and in fact a very convenient application of the present invention is to the pumps described and claimed in my co-pending applications, Serial Nos 275,453-6, filed May 24, 1939, and 330,224, filed April 17, 1940; and Serial Nos. 392,700, filed May 9, 1941, and 393,268, filed May 13, 1940.

Where, as is usual, the working chamber has

lateral, e. g., tangential, ports, one port may selectively serve as an inlet port and one as an outlet port depending upon the direction of rotation of the rotor and vanes; if the ports are tangential and lead from the working chamber in the same direction and the rotor is displaced in the working chamber in such direction, a short flow through the apparatus is available, the flow-through being longer when the barrel is displaced in the working chamber in the opposite direction. In either case however the direction of rotation of the rotor and consequently of the flow of the gaseous medium through the apparatus may be chosen at will.

15 An object of the present invention is to adapt the pump, without unduly increasing its bulk and weight, so that the rotor may be rotated in either direction without reversing the flow of the gaseous medium through one part of the apparatus. For example in the case of a cabin supercharger, it may be desired to discharge air unpolluted with oil used for lubricating the pump through an oil separator and/or it may be required to pass the air discharged from the working chamber over a heating or other air treating apparatus. It may be desirable in other cases to allow cold incoming air to pass over bearings or other parts liable to run hot. In any of these cases a uni-directional flow through the appropriate part of the apparatus is required irrespective of the direction of rotation of the rotor and vanes. On the other hand, a pump which can only work effectively when run in one direction is very disadvantageous when the pump is a unit which may have to be coupled to a shaft or other appropriate part the direction of rotation of which is not known when the pump is made.

20 Another object of the present invention is to provide a pump apparatus which is ported to permit of the desired uni-directional flow through a passage or chamber in the apparatus where such a flow is required, but will also be capable of running in either direction of rotation, and which is adapted to be coupled to a source of drive or prime mover external to the apparatus and according to this invention, the working chamber of the pump is provided with two pairs of ports, of which one of one pair and one of the other are arranged to be closed at any one time to permit the flow through the working chamber in one direction, whilst these two ports are opened and the other two closed to permit the flow to take place in the reverse direction when the direction of rotation of the rotor and vanes

25

30

35

40

is reversed, and the ports of one of the pairs communicate with a common annular passage formed in an axial extension of the casing around the or a shaft of the rotor so that the displaced medium is caused to flow in the same direction irrespective of the direction of rotation of the external driving motor or the like to which the pump is coupled and of the direction of flow through the working chamber.

Another object of the invention is to utilize as part of the passage through the apparatus for the gaseous medium a passage or chamber which exists between spaced anti-friction bearings which are inserted through one end of an extension containing a shaft of the rotor in order to obtain the desired unidirectional flow without unduly increasing the size and bulk of the apparatus.

A further object of the invention is to provide a standardized pump casing and detachable components attachable thereto selectively after the direction in which the pump is to rotate is known.

A further object of the invention is to reduce the length of path for the gaseous medium through the apparatus as far as possible consistent with permitting the desired unidirectional flow irrespective of the direction of rotation of the external driving motor.

Preferably automatic non-return valves are used in the pair of outlet ports, so that when the correct inlet port has been left open and the other plugged or closed, the pump is automatically adapted to operate in the given one of the two directions of rotation.

To provide these alternative ports in a convenient manner the pump is preferably provided with alternative lateral ports and with alternative end ports. The lateral ports are preferably arranged one on one side and one on the other side of the longitudinal axis of the pump and may lead approximately tangentially in abreast relation into the working chamber. The end ports direct the air discharged from the working chamber towards the end of the pump either in a direct path or in an angled or inclined path and preferably lead to an annular passage having a single outlet which may extend laterally, e. g., radially. Alternatively the lateral ports may be the delivery ports and the end ports the suction ports, e. g., where it is desired to use the incoming cold air to cool the rotor shaft.

A notably compact arrangement is produced by providing the casing of the pumping chamber with an axial extension and arranging for an extension of the rotor barrel which forms the rotor shaft or journal to rotate in such extension of the casing, the discharge ports being formed in such extension so that whichever port is in action the air flow is from the working chamber unidirectionally through the extension and then a single port which will be a discharge port, or in other forms of apparatus an inlet port which may extend axially but is conveniently arranged laterally, e. g., radially, and is in communication with the annular chamber with which the two ports communicate. The alternative end ports may be so arranged as to direct the air flow first axially and then towards the rotor shaft to the annular chamber or vice versa where the single port is an inlet port.

Where the rotor barrel is supported cantilever fashion, as described in my co-pending applications aforesaid, by spaced bearings, preferably

anti-friction, e. g., ball, bearings co-operating with the rotor shaft in the casing extension, an annular chamber is already present in the extension between the spaced bearings so as to allow the two bearings to be inserted into the casing extension from one end of the latter. I can therefore introduce the alternative porting system into such a pump with very little extra weight of metal or increase in bulk by providing the working chamber with two lateral ports as is ordinarily required, but making these ports both inlet ports or both outlet ports, and by providing the alternative end ports as short passages in the casing around the inner bearing, these ports placing in communication with the working chamber the said annular passage which is ordinarily sealed off therefrom. A single delivery or suction port is provided for this passage.

When non-return valves are employed, they may be of any convenient compact form mounted in the end alternative delivery ports so that automatically the pressure produced within the working chamber opens the one port whilst the other port remains closed during the working of the pump.

I employ a form of non-return valve which will be readily responsive to the pressures within the pump chamber. In the form of apparatus hereinafter described, the valve opens against the resistance of a comparatively light spring and provision is made for so securing the valve in position in the port as not to vary, as a result of fitting the valve to the pump, the predetermined resistance which the spring offers to the opening of the valve. Another form of valve which is suitable is one composed of one or more annularly slotted spring diaphragms, e. g., of the Hoehiger type.

The provision of the non-return valves is advantageous because it obviates the necessity for the user to determine which of the discharge ports is to be closed. The suction port which is not wanted has to be plugged and it is a simple matter to ascertain by means of a manometer that the proper suction port has been left open after connecting up the pump and having plugged one port.

In order that the invention may be more readily understood, reference is hereinafter made to the accompanying drawings depicting two forms of apparatus incorporating the present porting system.

Fig. 1 is a longitudinal sectional elevation of the first form of apparatus, Fig. 2 is a longitudinal sectional elevation at right angles to Fig. 1, and Fig. 3 is a half-sectional end view of the apparatus, Fig. 1 being taken on the line 1-1 of Fig. 3 and Fig. 2 on the line 2-2 of that figure. Fig. 4 is a fragmentary view of a modified device for closing one delivery port and this device is interchangeable with the plug, Fig. 5, which is used in the other delivery port to keep this open while shutting off the port from the exterior of the pump. Fig. 6 is an external view from the same aspect as Fig. 1 and Fig. 7 an external view from the same aspect as Fig. 2. Fig. 8 is a longitudinal elevation, Fig. 9 an end view, Fig. 10 a plan view and Figs. 11 and 12 sectional plan views on the line A-B, Fig. 8 showing diagrammatically how the pump may be adapted for selectively by-passing the passage around the shaft. Fig. 13 is a view similar to Fig. 9 of a modified construction which may be employed to achieve the same results when the

direction of rotation of the pump is previously known. Fig. 14, is a part longitudinal sectional elevation from the same aspect as Fig. 2, showing how the valves which control communication between the working chamber and the said passage may be mounted in a separate fitting which is ribbed to promote cooling, Fig. 15 being a half-plan of such fitting and Fig. 16 an end view thereof. Fig. 17, is a fragmentary sectional elevation from the same aspect as Fig. 3 of a modified construction of the ports so that the port which is the inlet in Fig. 3 is applicable as the outlet by reversing the direction of flow through the passage around the shaft.

The apparatus chosen for illustration of the present invention is that described and claimed in our co-pending application Serial No. 393,268, in which a uni-directional flow is required, irrespective of the direction of rotation of the rotor and vanes, of the air discharged through an oil-separator A into the occupied interior of the aircraft or to the de-icing equipment thereof. In this form of apparatus the flow is always from the working chamber to a single discharge port more remote from such chamber.

The pump apparatus comprises a casing 1 providing a working chamber 2 of cylindrical form in which is eccentrically mounted the barrel 3 of a rotor, the shaft 4 of which projects into an extension 5 of the casing. The barrel wall is slotted to house oscillatable bearing pins 6 which are themselves slotted or similarly formed slidably to receive the vanes 7 which have intercalated eyes 8 which are rotatably supported by a spindle 9 which is fixed to the end wall 10 of the casing and projects cantilever fashion into the working cylinder. Both the inside of the rotor barrel and the spaces between the barrel and the cylindrical wall of the working cylinder are usefully employed in the displacement of the air or other gaseous medium, the end wall 10 being divided into two components, the inner wall component 11 being appropriately ported at 12, 13, 14 and 15 to co-operate with the conduplicated compartments of the chamber 16 between the inner component 11 and the outer component 17 of the end wall. These compartments are formed by a dividing web 17a on the outer wall component. I do not propose to give a fuller general description of the pump, since it is fully described in my aforesaid applications, but I draw particular attention to the fact that the barrel of the rotor is supported cantilever fashion in the working chamber by the support of the rotor shaft by means of the spaced ball bearings 18 and 19. In my previous applications the annular passage 20 provided between these two bearings is substantially closed off from the working chamber.

In accordance with the present invention, two inlet ports 21 and 22 lead into the working chamber substantially tangentially thereto and preferably from the same side of the chamber as that on which the barrel is displaced and either one of these ports is adapted selectively to be closed by a plug 23 which is shown for the purpose of illustration as closing the port 22, as it does when the rotor turns in the direction shown by the arrow A. This plug is removable and insertable into the other port when the rotor is required to run in the reverse direction.

From the working chamber two outlet ports 24 and 25 communicate with the aforesaid annular passage 20 by a right-angled bend and the said passage is provided with a single delivery

port 27. The outlet ports 24 and 25 lie in the casing outside of the inner bearing 18. The single delivery port 27 is conveniently near the remote bearing 19.

5 In Figs. 1 to 3 the outlet ports 24 and 25 are each controlled by a non-return valve 28 which opens by the pressure of the gaseous medium within the pump chamber one port being always arranged on the suction side and the other on 10 the delivery or pressure side whichever direction of rotation is selected so that only one valve is open at a time. Each such valve is opened against the pressure of a light spring 29 which renders the valve responsive to comparatively low pressures. The valve-securing plug 30 positions the valve through the medium of an intermediate ported slide 31 which is forced against a shoulder 32 by a stiff spring 26 while screwing-in plug 30. Consequently the compression of the light valve 15 spring 29 is unaffected by the extent to which the plug is screwed into its socket.

In the alternative illustrated in Figs. 4 and 5, either of the outlet ports may be selectively closed from the exterior of the pump and arranged to 20 close the working chamber from the passage 20 by a plug 33 screwed at 34 into the casing and having a stem 35 which closes communication between the working chamber and the passage 20. The companion plug 36, Fig. 5, is used in 25 the other outlet port and serves to allow communication between the working chamber and the passage 20 although closing off the port to the exterior of the apparatus. These plugs are 30 interchangeable and are positioned according to 35 the direction of rotation of the rotor.

It will be observed that the valve means in Figs. 1 to 3 are, like the plugs just described, removable from the exterior of the apparatus, and like the plugs they serve to close the ports to the exterior of the apparatus.

The extension of the casing may be integral with the cylindrical part of the casing which forms the outer wall of the working chamber and may be bored out centrally to receive the ball bearings and the oil separator (when this is provided). The delivery ports 24 and 25 may be formed by bores parallel to the axis of the working chamber in offset chambers 37 of said casing and slot-like bores or ports 26a milled from the inside at right angles thereto lead to the passage 20. It may, however, be more convenient in some cases to form the extension in separate parts, e. g., parts secured together by peripheral engagement. The said bores in the offset chambers may be formed from the rear and may have lateral ports or openings 26b by which the bores in the offset chambers communicate with the working chamber. Thus one offset chamber has an inlet port 21 and a delivery port 24 and the other offset chamber corresponding ports 22, 25. The lateral or radial common outlet 27 may be connected with the large shouldered central passage by a short slot-like passage 39 milled from the inside.

60 The passage 20 within the casing extension 65 may be sealed at the remote end against exterior communication through the remote bearing races in any suitable way, e. g., by the sleeve 40 and rings 41 as described in my co-pending application No. 373,559 aforesaid or by providing sealing rings or annuli between the two races of the outer ball bearing.

70 The apparatus illustrated may be used for 75 supplying compressed air to the interior of the

air-craft or to the de-icing equipment. The uni-directional flow of the air through an oil separator is desirable in the latter case in order to avoid damaging access of lubricating oil from the pump to the rubber of such equipment. A stationary form of separator is disclosed, but a rotary or centrifugal form as in my aforesaid co-pending application Serial No. 392,700 may equally serve.

The construction of pump described is of especial value where a standardized product is required. For example it may be desired to use the pump, or to use it sometimes, without relying upon a unidirectional discharge or entry of the displaced medium and in this case both of the ports which communicate with the annular passage may be closed and the other two ports 21 and 22 opened, one as an inlet port and one as a discharge port. When the direction of rotation is known, the same standard pump casing may be used with a spring valve, as shown in Fig. 2, or other non-return valve, in one outlet port and a plug as shown in Fig. 4 in the other outlet port, thereby minimizing the liability of leakage past a non-return valve which is never required to be open to the passage 20.

Referring to Figs. 8 to 12 it is allowable to bridge each of the inlet ports 21 and 22 and the single discharge port 27 by a short internal passage or (as shown) external pipe 42, 42a, 42b containing a valve 43 and an intermediate exit 44 so that whichever port (port 21 in the example shown) is in use as the inlet port, by appropriately positioning the valve, the other of the inlet ports, port 22 in the illustration can be made an outlet so that the air can be discharged directly through such exit 44 instead of passing through the passage 20, see Fig. 11, or alternatively, the valve can be operated to compel the air to reach such exit only after passing through such passage (see Fig. 12). This is especially convenient when the apparatus is to be used for the dual purpose of a vacuum pump for operating instruments and as a pressure pump for operating de-icing equipment, since when the pump is operating the instruments only, the valves can be moved to permit the direct discharge (by-passing the passage 20) through such exit, whereas when the pump is to operate de-icing equipment the valves are operated to compel the air to pass through the passage 20 and the separator on its way to such exit. The inlet not used is plugged to the exterior, see plug 45, so that the discharge is past the valve and through the exit 44.

When the direction of rotation is known, one of such pipe components 42a, 42b need be fitted (see Fig. 13, which has pipe component 42b only). If desired, in order to simplify the casting of the casing of the apparatus, and in order to cool the air from the working chamber before passing around the rotor shaft, externally ribbed tubes 46 see Figs. 14 to 16 may be attached to the pump casing by bolts 47 to form the ports between the working cylinder and the passage 20 and the ribs or fins 48 may be arranged in the slip-stream, or one of such tubes may be fitted if the direction of rotation is known. The casing may be appropriately formed at 49 to enable such a tube or tubes to be readily coupled to it by way of the flanges 50, 51.

Each fitting forms that part of the offset chamber which comprises the delivery port, see Fig. 14, where the chamber that includes port 24 is shown. This said part is generally of tubular

form to provide the main bore of the delivery port 24, which runs parallel to the axis of the working chamber, the air which passes through said bore being cooled by the action of the cold air passing externally over the cooling ribs. The interior air is thus cooled prior to entry to the separator. The valve 28 and associated parts are included in this fitting which is generally similar to the corresponding integral part of the casing of the form shown in Fig. 2, the lateral openings corresponding to those 26a, 26b in the latter form, being provided by openings 26c, 26d in the fitting registering with openings 26e, 26f in the casing.

Where the port 27 is used as an inlet port, the ports 24 and 25 as inlets to the working chamber and the ports 21 and 22 as outlets therefrom, the non-return valves may be provided in the latter ports (see Fig. 17) instead of in the end ports 24 and 25 which may be of the form shown in Figs. 4 and 5.

What I claim is:

1. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically arranged in said chamber, said barrel having one end open and in working relation to one end wall of the casing and the other end closed and in working relation to the other end wall of the casing and a shaft projecting from said closed end wall of the barrel, said rotor dividing said working chamber from the interior of said extension, said shaft extending from said barrel into said hollow extension, spaced anti-friction bearings supporting said shaft in said extension, a plurality of vanes slidable through the peripheral wall of the barrel and rotatable therewith and adapted to produce chambers of varying volume within said working chamber, said casing having two chambers offset from and communicating with the working chamber, a passage in said extension interior around said shaft and between said spaced bearings, each of said offset chambers having an inlet port and a delivery port, one of said ports for each chamber placing its said offset chamber in communication with said passage and the other of said ports for each chamber placing its said offset chamber in communication with the pump exterior, said passage having a port at its end remote from said offset chambers, separate closure means for closing the inlet port of one of said offset chambers, and separate closure means for closing the delivery port of the other of said offset chambers so that depending upon the direction of rotation of said barrel and vanes only one of the inlet ports and only one of the delivery ports remains open and the displaced medium moves in the same direction through said passage irrespective of the direction of rotation, the outer end of said shaft being constructed for coupling to an external driving means.

2. A high speed rotary pump apparatus according to claim 1, in which separate closure means are provided in both of said delivery ports, said separate closure means being adapted to open by pressure of the fluid created within the working chamber, and one of said means in one of said delivery ports being arranged to be subjected to such pressure during the rotation of the barrel and vanes and the other being ar-

ranged to be subjected to suction and remaining closed.

3. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically arranged in said chamber and comprising at one end at least a shaft, said rotor dividing said working chamber from the interior of said extension, said shaft extending from said barrel into said hollow extension, spaced anti-friction bearings supporting said shaft in said extension, a plurality of vanes slidable through the peripheral wall of the barrel and rotatable therewith and adapted to produce chambers of varying volume within said working chamber, said peripheral wall of the casing having two local enlargements providing chambers offset from and communicating with the working chamber, a passage in said extension interior around said shaft and between said spaced bearings, each of said offset chambers having an inlet port and a delivery port, one of said ports for each chamber placing its said offset chamber in communication with said passage and the other of said ports for each chamber placing its said offset chamber in communication with the pump exterior, said passage having a port at its end remote from said offset chambers, separate closure means for closing the inlet port of one of said offset chambers with the running of the pump in a chosen direction of rotation and separate means for closing the delivery port of the other of said offset chambers so that depending upon the chosen direction of rotation of said barrel and vanes only one of said inlet ports and only one of said delivery ports remain open and the displaced medium moves in the same direction through said passage irrespective of the direction of rotation.

4. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically arranged in said chamber, said barrel having one end open and in working relation to one end wall of the casing and the other end closed and in working relation to the other end wall of the casing, and a shaft projecting from said closed end wall of the barrel, said rotor dividing said working chamber from the interior of said extension, said shaft extending from said barrel into said hollow extension, spaced anti-friction bearings supporting said shaft in said extension, a plurality of vanes slidable through the peripheral wall of the barrel and rotatable therewith and adapted to produce chambers of varying volume within said working chamber, said casing providing two chambers offset from and communicating with the working chamber, a passage in said extension around said shaft and between said spaced bearings, each of said offset chambers having a port which serves as an inlet to the working chamber and having a port which serves as a delivery port therefrom, one of said ports for each chamber placing its offset chamber in communication with said passage, said passage having a port at its end remote from said offset chambers, separate closure means

for plugging one or the other of said inlet ports in accordance with the direction of shaft rotation and automatic valves in each of said delivery ports adapted to open under the pressure 5 and to close under the suction prevailing in the working chamber so that in either direction of rotation of said barrel and vanes, the displaced medium moves in the same direction through said passage, the outer end of said shaft being 10 constructed for coupling to an external driving means.

5. A rotary pump apparatus according to claim 3, in which one port of one offset chamber and the corresponding port of the other offset chamber are directed tangentially to the working chamber and symmetrical to both the working chamber and the rotor barrel, said tangentially directed ports being disposed on that side of the working chamber on which the barrel is situated and the other ports of said offset chambers being each situated nearer to their companion tangentially directed ports than to each other.

6. A rotary pump apparatus according to claim 1, comprising means for sealing the outer end 15 of the passage, a mounting plate on the casing beyond the end of the passage for attaching the apparatus to a source of drive, said shaft extending through said plate, and said passage having its port remote from the working chamber 20 being each situated nearer to their companion tangentially directed ports than to each other.

7. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically arranged in said chamber, said barrel having one end open and in working relation to one end wall of the casing and the other end closed and in working relation to the other end wall of the casing, and a shaft projecting from said closed end wall of the barrel, said rotor dividing 40 said working chamber from the interior of said extension, said shaft extending from said barrel into said hollow extension, spaced anti-friction bearings supporting said shaft in said extension, a plurality of vanes slidable through a wall of the barrel and rotatable therewith and adapted 45 to produce chambers of varying volume within said working chamber, said casing having two chambers offset from and communicating with the working chamber, a passage in said extension around said shaft and between said spaced bearings, each of said offset chambers having an inlet port and a delivery port, one of said ports for each chamber placing its said offset chamber 50 in communication with said passage and the other of said ports for each chamber placing its offset chamber in communication with the pump exterior, said passage having a port at its end remote from said offset chambers, separate closure means plugging one of the ports which place 55 said offset chambers in communication with the pump exterior and means for alternatively closing either one of the ports which place said offset chambers in communication with said passage, said last mentioned means comprising interchangeable plugs fitted from externally of the pump into said ports, one of said plugs being fitted in said offset chamber whose port which 60 communicates with the pump exterior is open for such communication, said one plug closing the port which communicates with the working chamber.

ber and the annular passage, and another of said plugs being fitted to the other of said offset chambers whose port which communicates between the working chamber and the pump exterior is closed, said last mentioned plug being formed to allow communication between the working chamber and the passage, so that depending upon the chosen direction of rotation of said barrel and vanes only one of said inlet ports and only one of said delivery ports remain open and the displaced medium moves in the same direction through said passage irrespective of the direction of rotation.

8. A rotary pump apparatus according to claim 4, in which each of said automatic valves has spring means and a positive stop, said spring means permitting the valve to open at low pressures, means co-operating with said positive stop to energize said spring to a predetermined amount, and separate means for securing said spring-energizing means up to said stop and stiffer spring means interposed between said separate means and said spring energizing means.

9. A rotary pump apparatus according to claim 4, in which one of said ports for each offset chamber communicates with the working chamber and the annular passage and opens to the exterior of the apparatus, said automatic valves being removably arranged in said port for each said chamber so as to close off the port to the exterior and to open or close communication between the working chamber and the passage depending upon whether the valve is subjected to pressure or not.

10. A high speed rotary pump apparatus for displacing gaseous medium which comprises a casing having a peripheral wall and end walls forming a working cylinder and having an axial extension provided with a hollow interior having a cylindrical opening into one end wall of the said cylinder the other end wall of the cylinder having an annular groove coaxial with said opening, said groove and said opening being eccentric to said cylinder, a rotor within said pump chamber comprising a shaft portion and a barrel portion which is open at one end, and has a wall at the other which closes that end of the barrel, said open end comprising a ring face intruding into said annular groove and the other end of said barrel intruding into said cylindrical opening, said rotor dividing said working chamber from the interior of said extension, said shaft extending from the closed end wall of said barrel through said hollow extension interior, spaced antifriction bearings supporting said shaft in said extension, a spindle rigidly fixed in said grooved end wall so as to project cantilever fashion into the working cylinder centrally thereof, a plurality of vanes provided with bearing eyes which are rotatably supported by said spindle and which constrain the vanes from centrifuging, slotted cylindrical bearing members oscillatable in the peripheral wall of said barrel, said vanes passing through the slots in said members and said members and said vanes being relatively slid able, said vanes being arranged to generate with the cylinder walls and with the inner and outer walls of the rotor barrel pump working chambers of varying capacity both inside and outside of said rotor barrel and said casing being ported to co-operate with said inside and outside working chambers, said casing providing two chambers offset from and communicating with the working chamber, an annular passage around said shaft between said

spaced bearings, each of said offset chambers having an inlet port and a delivery port, one of said ports for each chamber placing its said offset chamber in communication with said passage and the other of said ports for each chamber placing its offset chamber in communication with the pump exterior, said passage having a port at its end remote from the offset chambers, separate closure means closing the inlet port of one of said offset chambers and separate means for closing the delivery port of the other of said offset chambers for the running of the barrel and vanes in a chosen direction so that depending upon the direction of rotation of said barrel and vanes only one of said inlet ports and only one of said delivery ports remain open during such rotation and the displaced medium moves in the same direction through said passage irrespective of the direction of rotation, the outer end of said shaft being constructed for coupling to an external driving means, said bearings being constructed and proportioned so as wholly to support said rotor cantilever fashion out of contact with the working cylinder.

11. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically arranged in said chamber, said barrel having one end in working relation to one end wall of the casing and the other end in working relation to the other end wall of the casing and a shaft projecting from at least one end wall of the barrel, said rotor dividing said working chamber from the interior of said extension, said shaft extending from said barrel into said hollow extension and being supported in said extension, a plurality of vanes slidable through the peripheral wall of the barrel and rotatable therewith and adapted to produce chambers of varying volume within said working chamber, said casing having two chambers offset from and communicating with the working chamber, a passage in said extension interior around said shaft, each of said offset chambers having an inlet port and a delivery port one of said ports for each chamber placing its said offset chamber in communication with said passage and the other of said ports for each chamber placing its said offset chamber in communication with the pump exterior, said passage having a port at its end remote from said offset chambers, separate closure means for closing the inlet port of one of said offset chambers and means for closing the delivery port of the other of said offset chambers with the rotation of the barrel and vanes in a chosen direction so that depending upon the direction of rotation of said barrel and vanes only one of said inlet ports and only one of said delivery ports remains open and the displaced medium moves in the same direction through said passage irrespective of the direction of rotation, the outer end of said shaft being constructed for coupling to an external driving means.

12. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically

ly arranged in said chamber, said barrel having one end in working relation to one end wall of the casing and the other end in working relation to the other end wall of the casing and a shaft projecting from at least one end wall of the barrel, said rotor dividing said working chamber from the interior of said extension, said shaft extending from said barrel into said hollow extension and being supported in said extension, a plurality of vanes slidable through the peripheral wall of the barrel and rotatable therewith and adapted to produce chambers of varying volume within said working chamber, said casing having two chambers offset from and communicating with the working chamber, a passage in said extension interior around said shaft, said passage having a port at its end remote from said offset chamber, each of said offset chambers having an inlet and a delivery port, one of said ports for each chamber placing its said offset chamber in communication with said passage, a conduit placing the other of said ports for each chamber in communication with said port in said passage, an intermediate opening from said conduit and valve means in said conduit operative to couple said intermediate opening directly with the working chamber and thereby by-pass said passage or to couple said opening for communication with said passage, separate closure means for closing the inlet port of one of said offset chambers and means for closing the delivery port of the other of said offset chambers for a chosen direction of rotation of the barrel and vanes so that depending upon the chosen direction of rotation of said barrel and vanes only one of said inlet ports and only one of said delivery ports remains open and the displaced medium moves in the same direction through said passage irrespective of the direction of rotation, the outer end of said shaft being constructed for coupling to an external driving means.

13. A high speed rotary pump apparatus for displacing gaseous medium which comprises a casing having a peripheral wall and end walls forming a working chamber and having an axial extension provided with a hollow interior opening through one of said end walls into said chamber, a rotor having a barrel portion eccentrically

arranged in said chamber, said barrel having one end in working relation to one end wall of the casing and the other end in working relation to the other end wall of the casing and a shaft projecting from at least one end wall of the barrel, said rotor dividing said working chamber from the interior of said extension, said shaft extending from said barrel into said hollow extension and being supported in said extension, a plurality of vanes slidable through the wall of the barrel and rotatable therewith and adapted to produce chambers of varying volume within said working chamber, said casing having two chambers offset from and communicating with the working chamber, a passage in said extension interior around said shaft, said passage having a port at its end remote from said offset chamber, each of said offset chambers having an inlet and a delivery port, one of said ports for each chamber placing its said offset chamber in communication with said passage, a conduit placing the other of said ports for each chamber in communication with said port in said passage and with the corresponding port in the other offset chamber, an intermediate opening from said conduit and valve means in said conduit operative selectively to couple said intermediate opening directly with the last named port of one offset chamber and to close it from the last named port of the other offset chamber and to by-pass said passage or to close said opening from both said communicating ports of the offset chambers and to couple said opening for communication with said passage, separate closure means for closing the inlet port of one of said offset chambers and means for closing the delivery port of the other of said offset chambers for a chosen direction of rotation of said barrel and vanes so that depending upon the chosen direction of rotation of said barrel and vanes only one of said inlet ports and only one of said delivery ports remain open and the displaced medium moves in the same direction through said passage irrespective of the direction of rotation, the outer end of said shaft being constructed for coupling to an external driving means.

FRANK CHRISTIAN FULCHER.
